(57) **CLAIM**

The ornamental design for a track for display shelving, as shown and described.

DESCRIPTION

FIG. 1 is a perspective view showing our new design of a track;

FIG. 2 is a front view of the track of FIG. 1, the rear view being a mirror image thereof;

FIG. 3 is a left side view of the track of FIG. 1;

FIG. 4 is a top view of the track of FIG. 1;

FIG. 5 is a right side view of the track of FIG. 1;

FIG. 6 is a bottom view of the track of FIG. 1;

FIG. 7 is an enlarged front view of a section of the base of the track shown in FIG. 2, taken along line “FIG. 7” of FIG. 2;

FIG. 8 is a perspective view of a second embodiment of our new design;

FIG. 9 is a perspective view of a third embodiment of our new design;

FIG. 10 is a perspective view of a fourth embodiment of our new design; and,

FIG. 11 is an enlarged front view of a section of the base of the design shown in FIG. 10.
